REMOVAL OF IMPURITIES FROM HYDRO-CARBON OXIDATION PRODUCTS

William H. Clingman, Jr., Texas City, Tex., assignor to The American Oil Company, Texas City, Tex., a corporation of Texas

No Drawing. Application June 5, 1956
Serial No. 589,370

4 Claims. (Cl. 260—533)

This invention relates to the production of carboxylic acids by the oxidation of hydrocarbons and more particularly it concerns the removal of impurities from the hydrocarbon oxidation products.

When nitric acid or nitrogen dioxide are used in the oxidation of hydrocarbons for the production of carboxylic acids, organic nitrogen compounds are produced as by-products. For example when cyclohexane is oxidized to adipic acid, using nitric acid or nitrogen dioxide, the liquid portion of the oxidation products contains a small amount of undesirable "nitro" compounds which are exceedingly difficult to remove. These "nitro" compounds consist of nitrites, nitro derivatives etc. of the hydrocarbons oxidized. Unless these impurities are removed from the adipic acid, they interfere with the subsequent use of adipic acid in manufacturing good quality ultimate products such as nylon etc.

An object of this invention is to provide a process for removing the organic nitrogen compound impurities from the hydrocarbon oxidation products obtained when using nitric acid or nitrogen dioxide as the oxidizing means. Another object is to provide a process which enables the recovery of a high percentage of the carboxylic acids produced while still maintaining a high degree of organic nitrogen compound removal therefrom. Other objects and advantages of the invention will be apparent from the more detailed description thereof.

It has been found that the organic nitrogen compound impurities, which are formed during the oxidation of hydrocarbons to carboxylic acids in the presence of nitric oxide or nitrogen dioxide, can be removed from the carboxylic acids formed by neutralizing an aqueous solution of the oxidation products containing the carboxylic acids so that it has a pH of at least 7, but preferably at least 8 and not more than 10, and then contacting the aqueous solution with an activated carbon. The organic nitrogen compound impurities are adsorbed upon the activated carbon, the carboxylic acids remaining as salts in the aqueous solution. Thereafter the activated carbon is separated from the aqueous solution and the carboxylic acids recovered from the aqueous solution by procedures well-known in the art.

Although the process of this invention is applicable to the removal of organic nitrogen compound impurities contained in the oxidation products produced by oxidizing aliphatic hydrocarbons such as olefins and paraffins having from 2 to 20 carbon atoms to carboxylic acids using nitric acid or nitrogen dioxide with or without free oxygen, it will be described principally with reference to the removal of such impurities from the products obtained by oxidizing naphthenes to dicarboxylic acids. The oxidation of naphthenes such as cycloalkanes having 5 or 6 carbon atoms in the ring and their methyl-, ethyl-, propyl-, or butyl-substitution products to produce adipic acid (and also succinic and glutaric acids) and its alkyl substitution products by the use of NO_2 as the oxidizing means is known. The use of nitric acid in the oxidation of naphthenes is also a widely known process. Detailed

2

descriptions for carrying out the oxidation process are available in the prior art.

After the oxidation reaction has been completed, the gaseous products are separated from the normally liquid oxidation products. The liquid oxidation products generally consist of two phases, a supernatant layer of unreacted hydrocarbons and an aqueous layer containing carboxylic acids contaminated with the organic nitrogen compound impurities. To insure full recovery of the carboxylic acids, the separated hydrocarbon layer is washed with water to dissolve the carboxylic acids, and the washings are then added to the aqueous layer of oxidation products. The general practice customarily followed in recovering the adipic acid from the aqueous solution consists of cooling the aqueous solution to a temperature at which the adipic acid crystallizes therefrom. The crystals of adipic acid, however, are contaminated with the organic nitrogen compound impurities. In the process of this invention, the organic nitrogen compound impurities are removed from the aqueous solution before recovering the adipic acid and/or other carboxylic acids from the aqueous solution. If desired, the invention may be practiced on the crystallization mother liquors or at any other stage in the recovery of the acids from the aqueous solution of oxidation products.

The organic nitrogen compound impurities cannot be removed by the use of solvents such as ether, chloroform etc. because the solvents extract the carboxylic acids as well as the nitrogen compound impurities. Because of their very low volatility, the organic nitrogen compounds cannot be separated by vacuum distillation. The separation cannot be effected by forming insoluble salts of the carboxylic acids since the nitrogen compounds are adsorbed on these salts. I have found, however, that the organic nitrogen compounds can be removed from the aqueous solution of carboxylic acids by adsorbing them upon an activated carbon in a neutral solution. If the aqueous solution of the liquid oxidation products has a pH of less than 7, the activated carbon will adsorb the adipic acid as well as the organic nitrogen compounds and only a minor amount of adipic acid will be recovered from the attempted purification. If the pH of the aqueous solution is at least 7, the organic nitrogen compounds are adsorbed upon the activated carbon but the adipic acid is adsorbed to only a small extent. Thus a pH of 7 to about 14 can be used. The amount of adsorption of adipic acid upon the activated carbon can be minimized by using a pH of at least 8 but not more than about 10. This enables maximum recovery of high purity adipic acid.

In neutralizing the aqueous solution of the liquid oxidation products, a basic reagent, preferably an alkali metal containing basic reagent, is employed. For example, the alkali metal hydroxides, oxides, carbonates; the alkaline earth metal oxides, hydroxides, carbonates, sulfides etc. are highly useful for this purpose, although obviously many other basic reagents such as ammonium hydroxide, organic amines such as alkanol amines, etc. can be used. It is preferred to carry out the neutralization prior to contacting the aqueous solution with the activated carbon since this enables greater recoveries of adipic acid i. e. lesser amounts of adipic acid are adsorbed upon the activated carbon.

The aqueous solution of the liquid oxidation products which contains the adipic acid and organic nitrogen compound impurities may be contacted with the activated carbon in a batch contacting process or in a continuous process wherein the aqueous solution is slowly percolated through the layer of activated carbon. A multi-stage process or counter current operation may be used. The contacting is carried out for a period of time sufficient to adsorb the nitrogen compounds e. g. 1 minute to 2

hours. It may be carried out at temperatures of from 20 to 50° C., although higher or lower temperatures may of course be used, depending in part upon the boiling point of the carboxylic acid, to be recovered.

The activated carbon which is used is a high surface material which is commonly known as activated carbon or activated charcoal. The total surface area of such activated carbons generally ranges between 2×10^4 and 6×10^4 sq. cm. per gm. It is generally prepared by carbonizing wood, peat, cellulose waste, bones, coconut shells, corn cobs or the like to produce a carbon which is then crushed to the desired size, following which the crushed material is activated by heating to an elevated temperature in an atmosphere of steam, carbon dioxide etc. until the desired activity has been attained. An activated charcoal prepared from coconut shells is highly satisfactory. The activated carbon is contacted with the aqueous solution of liquid oxidation products containing carboxylic acid and organic nitrogen compound impurities in an amount sufficient to adsorb the nitrogen compounds contained therein. Thus the amount employed, based upon the amount of aqueous solution, depends upon the concentration of the organic nitrogen compounds. Usually one kilogram of the activated carbon will adsorb from 2 to 3 gms. of the organic nitrogen compound impurities. Complete adsorption of these impurities is indicated by a change in color of the aqueous solution from yellow (the yellow color being caused by the organic nitrogen compound impurities) to water white. The activated carbon which has become saturated with the organic nitrogen compounds can be partly regenerated by treatment with a caustic solution such as 1 N NaOH. After the organic nitrogen compound impurities have been adsorbed from the neutralized aqueous solution of the oxidation products, the adipic acid can be recovered by well-known procedures. For instance, the neutralized solution may be acidified to release the adipic acid, followed by distillation or crystallization to recover the adipic acid.

Certain laboratory experiments were carried out relative to the purification of adipic acid solutions contaminated with organic nitrogen compound impurities. In a typical experiment 208.1 gms. of an aqueous solution containing 1.09 gms. of adipic acid per 100 gms. of solution were placed in a beaker. Organic nitrogen compound impurities obtained from the oxidation of tertiarybutylcyclohexane with HNO_3 and O_2 (120 p. s. i. g.) at 90-95° C. in the presence of H_2SO_4 were used in certain experiments and the organic nitrogen compound impurities obtained by the NO_2 oxidation of tertiarybutylcyclohexane were used in others. The organic nitrogen compound impurities were added in the amount of 0.04 gms. to the 208.1 gms. of solution. The adipic acid used was commercial adipic acid having a M. P. of 154°-155° C. Two procedures were employed in the purification experiments. In method A the aqueous solution of adipic acid and organic nitrogen compound impurities was neutralized by adding thereto an amount of 2 N KOH or NaOH solution until the proper pH was reached and the activated carbon added thereafter. In method B the activated carbon was added to the aqueous solution of adipic acid and organic nitrogen compounds prior to neutralizing the aqueous solution. The activated carbon employed was 49.8 gms. of 50 min. 6-14 mesh activated charcoal. The mixture was stirred at about 30° C. for about one hour. Thereafter the charcoal was filtered off and washed three times with distilled water.

The amount of adipic acid in the treated solution was determined by precipitating its insoluble silver salt, dissolving the salt in 1 N HNO_3 , and determining the silver in the solution by titration with NaCl . In certain of the

experiments the charcoal treated solution was evaporated to reduce its volume and the adipic acid precipitated by adding HCl. The adipic acid obtained in this manner was dried at 110° C. without recrystallization, and its melting point determined. A one degree lowering of the melting point corresponds to a purity of about 98.4-99.0%. A two degree lowering of the melting point corresponds to a purity of 96.7-98.0%. The absence of the organic nitrogen compounds from the charcoal treated solutions was shown by these melting points and the fact that the characteristic red and yellow salts of the organic nitrogen compounds were not detected in the basic solutions. The original untreated solutions were yellow in color while the color of the charcoal treated solutions was water white. The effectiveness of the treatment with charcoal at various pH's using methods A and B is shown in Table I which follows:

Table I

pH	Adipic Acid Recovery, percent		Melting Point of Recovered Adipic Acid, ¹ °C.
	Method A	Method B	
25	0.8		
7	75.4	62.5	153-154
8	93.3	75.7	
10	97.2		
12	85.9		152.5-153.5
5-N NaOH ²	52.5		153-154

¹ Melting point of adipic acid charged = 154°-155° C. Literature value for M. P. of adipic acid = 153° C.

² Adipic acid recovered using Method B.

³ pH ca. 14.

- It is evident from the above table that the purified adipic acid has a purity of approximately 99 mol percent. It is also apparent that the pH at which the charcoal treatment is carried out is critically important in its effect upon the amount of adipic acid recovered, i. e., it must be at least 7 and is preferably between about 8 and 10. It will also be noted that method A, wherein the adipic acid solution is neutralized before adding the activated charcoal, enables a greater recovery of adipic acid than does method B wherein the adipic acid solution is neutralized after the activated charcoal has been added.
- 45 Thus having described the invention what is claimed is:
1. A process for removing organic nitrogen compound impurities from the normally liquid oxidation products produced by oxidizing naphthalene hydrocarbons to carboxylic acids using an oxidizing agent selected from the group of nitrogen compounds consisting of nitric acid and nitrogen dioxide which removal process comprises contacting a neutralized aqueous solution of the normally liquid oxidation products having a pH of at least 7 with an activated carbon whereby the organic nitrogen compound impurities are removed from the solution of normally liquid oxidation products by adsorption on said carbon, and separating the solution of normally liquid oxidation products from the activated carbon containing adsorbed organic nitrogen compound impurities.
  2. The process of claim 1 wherein the aqueous solution of the normally liquid oxidation products is neutralized with a basic reagent prior to contacting said aqueous solution with activated carbon.
  3. The process of claim 1 wherein the pH is at least 8 but not more than 10.
  4. The process of claim 1 wherein the oxidizing agent is nitrogen dioxide.
